UNITED STATES PATENT OFFICE.

JOHN A. STONE, OF DERRY, NEW HAMPSHIRE, ASSIGNOR TO UNITED SHOE MACHINERY COMPANY, OF PATERSON, NEW JERSEY, A CORPORATION OF NEW JERSEY.

GUIDING DEVICE FOR GROOVING-TOOLS.

1,148,723.

Specification of Letters Patent.

Patented Aug. 3, 1915.

Application filed August 31, 1910. Serial No. 579,855.

To all whom it may concern:

Be it known that I, JOHN A. STONE, a citizen of the United States, residing at Derry, in the county of Rockingham and State of New Hampshire, have invented certain Improvements in Guiding Devices for Grooving-Tools, of which the following description, in connection with the accompanying drawings, is a specification; like referring characters on the drawings indicating like parts in the several figures.

This invention relates to channeling and grooving machines used in the manufacture of boots and shoes and more particularly to a device for conducting away the string of leather which is removed by the grooving tool. It is common in machines of this class to subject a sole to the action of a channeling knife and a grooving tool, the function of the knife being to produce a channel by raising a flap or lip near the edge of the sole, while that of the grooving tool is to cut a groove near the base of the channel for the reception of the stitches by which the sole is subsequently attached to the remaining portions of the shoe. These grooving tools, which are commonly tubular, remove by their action a comparatively slender string of leather from each sole; and this string after it passes through the tubular tool ordinarily falls back into the groove from which it was removed so that after the channeling and grooving operations have been completed it is necessary for the operator to lift up a portion of the flap and pull the string from the groove.

Accordingly, the general object of this invention consists in the provision with a grooving tool for removing a string of leather from a sole of means arranged in the rear of said tool for conducting said string away from the groove from which it was removed.

Another feature consists in the provision of a guiding member having a cut-away portion the purpose of which is to provide space for any twisting or crumpling of the string which may occur and thereby to lessen the tendency of said string to jam in said device. And this cut away portion is preferably provided in that side of the device which is remote from the sole so that the string will be kept clear at all times from the channel of the sole. It sometimes happens, however, that the string becomes

jammed, and in order to provide for such a contingency another feature of the invention consists in the provision of means for detachably connecting the conducting member with the grooving tool.

60

These and other features of the invention including certain details of construction and combinations of parts will be described in connection with the accompanying drawings and pointed out in the appended claims.

65

Referring now to the accompanying drawings: Figure 1 is a perspective showing certain parts of a channeling and grooving machine in which the present invention is embodied; Fig. 2 is a plan showing certain parts of the machine as they appear during the channeling and grooving of a sole, a string being shown issuing from the guiding device or string puller; and Fig. 3 is a perspective of the machine showing the grooving tool in operation upon a sole, the manner of attachment of the guiding device to the grooving tool being more clearly illustrated.

70

A feed wheel herein shown as comprising toothed sections 1 is arranged to be rotated by any suitable means and thereby to feed a sole beneath a presser foot 3 to a channeling knife 5 and a grooving tool 7, the edge of the sole being guided by a rotatable edge gage 9. The presser foot is fastened by means of screws 11 to a block 13, said block being horizontally adjustable on a second block 15 by means of a screw 17, said second block being vertically adjustable on the head of the machine by means of a second screw 19. The knife, which is of a common type, is adjustably fastened to its stock 21 by a member 23 provided with pins 25 which pass through semicircular channels in the shank of the knife. The shank 27 of the tubular grooving tool 7 is provided with a slot through which passes the shank of a headed clamping bolt 31. This bolt also passes through the stock of the grooving tool and its farther end is engaged by a nut, 100 not shown, whereby said tool is held firmly in adjusted position.

95

When a sole is fed through the machine, the knife acts as shown in Fig. 3 to cut a channel near the edge of the sole, while the grooving tool cuts a groove near the base of the channel.

105

With the construction thus far described the string of leather cut from the sole by the grooving tool after passing through said

110

- tool comes into contact with the channel flap and tends to fall back into the groove from which it was removed. In order to direct the string upwardly away from the groove a 5 guiding device 33 is arranged in the rear of the grooving tool. In the illustrated embodiment this guiding device consists of a tube having a portion of its upper wall cut away whereby the string may more readily escape and jamming of the string in the device is avoided. In order that the guiding device may be adjustably fastened to the grooving tool a slotted shank 35 is provided, a guideway being formed in its forward face as shown in Figs. 2 and 3 for the reception of the shank of the grooving tool, and through one wall of this guideway is threaded a set screw 37. The guiding device may thus be adjusted toward and from 10 the axis of the grooving tool to bring its bore into alinement with that of the tool. In order to insure that the guiding device, when adjusted, shall be held rigid with the grooving tool the walls of the shank 35 are 15 engaged by the head 39 of the bolt 31 so that the grooving tool and the guiding device may be firmly clamped to the tool stock. In the operation of the machine, the sole 20 is fed between the two disks and the presser foot and advanced to the channel knife and grooving tool which act to raise the channel flap and to cut a groove near the base of the channel as shown in Figs. 2 and 3, the guiding device receiving the string cut out by 25 the grooving tool and guiding it well up and away from the channel so that no further separation of it from the sole is required.
- Having described my invention, what I 30 claim as new and desire to secure by Letters Patent of the United States is:—
1. The combination with a grooving tool for removing a string of leather from a sole of a guiding device arranged in the rear of said tool for conducting said string away from the groove from which it was removed, said device comprising a member provided with a cut-away portion to permit the string to escape.
  2. The combination of a grooving tool

having a slotted shank and a guiding device having a similar shank fastened to the slotted shank of said tool and adapted to receive and guide away the string of leather removed by said tool, said device being adjustable toward and from the axis of said tool.

3. The combination of a grooving tool having a slotted shank, a guiding device arranged in the rear thereof and having a 60 similar shank and a clamping bolt passing through both slots and adapted to hold said tool and device rigidly together.

4. A machine of the class described having, in combination, a channeling knife, 65 means for feeding a sole thereto whereby a channel flap is formed on said sole, a tubular grooving tool arranged in the rear of said knife and adapted to remove a string of leather from said sole, and a member arranged in contact with the rear of said grooving tool and adapted to receive the string removed by said tool and to conduct said string above the top and away from 70 said channel flap.

5. The combination with a grooving tool for removing a string of leather from a sole, said tool being provided with a slotted shank the rear face of which coincides approximately with the rear end of the tool, of a 80 guiding device arranged in the rear of said tool for conducting said string away from the groove from which it was removed, and means for holding said guiding device in place.

6. The combination with a grooving tool for removing a string of leather from a sole, of a guiding device arranged in the rear of said tool for conducting said string away from the groove from which it was removed, 90 said device being adjustable transversely of the axis of the grooving tool.

In testimony whereof I have signed my name to this specification in the presence of two subscribing witnesses.

JOHN A. STONE.
